U.S. PATENT DOCUMENTS

D135,005 S 2/1943 Baumgardner

Design U.S. Appl. No. 29/412,280, filed Feb. 1, 2012.

(Continued)

Primary Examiner — Mark Goodwin

(74) *Attorney, Agent, or Firm* — Fish & Richardson P.C.

(57) **CLAIM**

The ornamental design for a field for control panel of road construction machine, as shown and described.

DESCRIPTION

FIG. 1 is a top view of the design for a field for control panel of a road construction machine; and, FIG. 2 is a top perspective view of the design of the field for control panel of a road construction machine.

1 Claim, 2 Drawing Sheets
